UNITED STATES PATENT OFFICE.

ABRAM MOSES, OF BALTIMORE, MARYLAND.

CARD-INDEX.

1,233,388.

Specification of Letters Patent.

Patented July 17, 1917.

Application filed January 30, 1917. Serial No. 145,374.

To all whom it may concern:

Be it known that I, ABRAM MOSES, a citizen of the United States, residing at Baltimore, State of Maryland, have invented new and useful Improvements in Card-Indexes, of which the following is a specification.

This invention relates to improvements in card indexes and more particularly to a reversible visible-card index.

10 It is the object of this invention to provide a frame for containing cards in which the top of each card is always visible and the frame so formed as to be similarly constructed on both sides to retain and display 15 cards on both sides. The frames may form complete indexes by themselves or may be pivotally attached at one side to a rotatable stand or other support forming a series of leaves thereon.

20 The advantages of this device are that it is light in weight and inexpensive to manufacture, can be stamped out of a single sheet of thin metal, is of the same construction on both sides and it is therefore reversible 25 to display cards on both sides, may be made to receive cards of any standard size and shape, and can be constructed to display a double row of cards on each side by stamping the double form from a single sheet of 30 metal.

While the preferred form of this invention is illustrated upon the accompanying sheet of drawing, yet it is to be understood that minor detail changes may be made without departing from the scope thereof.

Figure 1 is a view in front elevation with the central portion broken away of this improved device.

Fig. 2 is a view in side elevation of the 40 same.

Fig. 3 is a view in rear elevation of the same.

Fig. 4 is a bottom plan view of Fig. 1.

Fig. 5 is a fragmentary view of Fig. 1 45 showing the cards in position.

Fig. 6 is an enlarged detail, sectional view taken on the line 6—6 of Fig. 5.

Fig. 7 is a view in front elevation of the double construction reduced in size.

50 Fig. 8 is a detail view in side elevation of the card clip as applied to the cards.

Fig. 9 is an enlarged detail view in front elevation of a preferred form of clip.

In this index the cards may be inserted and removed and are supported one above 55 the other in the same general manner as described in my former Patent 1,126,062 of January 26, 1915.

The frame 1 for displaying the index cards 2 in accordance with this invention is 60 struck from a rectangular blank of metal, with the longitudinal sides slotted at regular intervals at right angles thereto forming a plurality of similar ears 3 and 4, the first slit on each side of the blank preferably 65 of greater distance from the top and bottom than the distance between the other slits for a purpose hereinafter explained, the top and bottom edges of the blank slotted an equal depth and parallel with the inner 70 ends of the longitudinal edge slits, the body of the blank offset along its longitudinal center line dividing it into two equal portions 5 and 6 lying in parallel planes which may be at right angles to the offset portion 75 or at a slight angle thereto. The body of the metal between the top slits is either entirely removed or similarly slotted at the edges of the offset portion and the metal therebetween removed and the metal be- 80 tween the bottom slits is similarly slotted at the edges of the offset portion and the metal therebetween removed, and the remaining metal on each side similarly slotted at regular intervals, for a purpose hereinafter de- 85 scribed.

The ears 3 and 4 along the longitudinal edges are alternately bent back first on one side and then on the other upon the adjacent body section to form card guides, the 90 guides being formed by the oppositely disposed ears being both bent toward each other or the guides may be staggered by bending the oppositely disposed ears upon opposite sides of the body. As it is desirable to have 95 the card-engaging portions 8 and 9 of the guiding ears lying in the same plane, the alternate ears 4 are formed with a right-angular portion 10 adjacent the body to compensate for the offset 7, while the re- 100 maining ears 3 are bent directly back upon the adjacent body. The metal between the top slits may be removed entirely or slotted at the edges of the offset 7 with the metal therebetween removed and the remaining 105 metal bent back closely upon the adjacent

- body-portions 5 and 6 to strengthen them, and the metal between the bottom slits is slitted at each edge of the offset with the metal therebetween removed and the remaining metal correspondingly slitted to form an equal number of ears 11 on each side and bent back upon the adjacent body to form card supports with the card-engaging portions 12 lying in the same plane as the card-engaging portions of the card guides. The card guides 3 are preferably provided with a struck-up rib 13 parallel to the edge of the frame for the attachment of an index tab.
- 15 The metal at each corner between the top and bottom slits and the adjacent ear slits is bent back and forth upon itself to form a pivot pin 14 for attachment to a rotary stand or other support, not shown.
- 20 The distance between the card guides is such that they will receive index cards of standard width between them and the cards are maintained in position to display the top of each card above the one next below 25 in the same general manner described in my prior Patent 1,126,062, above-mentioned, however, in this case only one card clip 15 is employed and is secured upon the card so that the rearward bent tongue extends in 30 the space formed by the offset portion 7 of the frame. The preferred form of clip is shown in Fig. 9 and is struck from a blank of metal having one longitudinal side 17 longer than the other with a prong 18 extending from the bottom and another prong 19 struck out of the body whereby the clip may be secured to the bottom of the card or if a greater amount of space on the card is desired to be displayed it may be readily 35 attached to the body of the card above the bottom as shown in Fig. 8. In order that the clip will be received in the recess of the frame formed by the offset it is only necessary to attach the clip a little to one side of 40 the center and the card will be received on both sides equally well with the longer longitudinal side 17 engaging the offset portion 7 over which it will readily slide and act as an additional guide for the card.
- 45 If desired, a frame adapted to display a double row of cards may be struck from a single sheet of metal in the same manner only the central portion is slitted to form guiding ears 3^a and 4^a leaving a portion 20 of the body extending between successive ears, as disclosed in Fig. 7.
- 50 This form of visible-card index has all the advantages of my above-said patent and in addition thereto employs only 55 one card clip, and being similar on each side is reversible and will receive and display cards on both sides, furthermore, it can be formed to display a double row of cards on each side from a single sheet of metal.

What I claim is:—

1. A visible-card index comprising a body having a longitudinal depression therein and card guides along the horizontal edges adapted to receive index cards having supporting clips for the cards above with the card support of the clips traveling in said depression. 65
2. A visible-card index comprising a body having a longitudinal central offset therein dividing the body into two similar portions, card guides along the longitudinal edges extending on front and back of the adjacent body-portions toward the offset adapted to receive on the front and back of the body index cards having supporting clips for the cards above with the card supporting clips traveling in the recesses formed by the offset. 70
3. A reversible visible-card index comprising a rectangular body having an offset along its longitudinal center causing the body to be of similar conformation on front and back, a plurality of integral card guides extending along each longitudinal edge on the front and back of the body with the card-engaging portion of the guides on each respective side in the same respective plane, a plurality of card supports extending upward along its bottom edge on the front and back of the body. 75
4. A reversible visible-card index comprising a rectangular body having an offset along its longitudinal center causing the body to be of similar conformation on front and back, a plurality of integral card guides extending along each longitudinal edge on the front and back of the body with the card-engaging portion of the guides on each respective side in the same respective plane, a plurality of card supports extending upward along its bottom edge on the front and back of the body, and a supporting pivot pin extending from each corner of the body. 80
5. A reversible visible-card index formed from a blank of metal to provide a rectangular body having an offset along its longitudinal center dividing the body into two portions lying in different planes with the body of similar conformation on front and back, a plurality of integral card guiding ears bent inward on the front and back of the body along each longitudinal edge, a plurality of integral card-supporting ears bent upward on the front and back along the bottom edge with the card-engaging portion of the supports and guides lying in the same planes on the respective sides of the body. 85
6. A reversible visible-card index formed from a blank of metal to provide a rectangular body having an offset along its longitudinal center dividing the body into two portions lying in different planes with the body. 90

body of similar conformation on front and back, a plurality of integral card guiding ears bent inward on the front and back of the body along each longitudinal edge, a 5 plurality of integral card-supporting ears bent upward on the front and back along the bottom edge with the card-engaging portion of the supports and guides lying in the

same planes on the respective sides of the body, and an integral supporting pivot pin 10 extending from each corner in the same plane as the adjacent body portion.

ABRAM MOSES.
